PAPER CUP

William G. Jopson, Williamsport, Pa., assignor to
 C. A. Reed Company, Williamsport, Pa., a corporation of Delaware

Application December 16, 1940, Serial No. 370,239

3 Claims. (Cl. 229—52)

This invention relates to cups intended for single use and such as are commonly made of paper, and has for an object to associate a handle with the cup, so formed that it may be pressed closely adjacent to the outside of the cup so as not to interfere with nesting of the cups in a stack as for packaging for shipment and dispensing, but which handle can be pulled outwardly into loop form without detachment from the cup when desired for handle use. Such a handle is of particular utility when the cup contains hot liquids which prevent holding of the cup between the fingers of the user.

A particular object of this invention is to so form the handle that it may be made up separately from the cup and may be firmly secured thereto by a mere interlocking engagement and without requiring the use of an adhesive or a separate fastener.

A further object is to provide a handle constructed identically at opposite ends and with cup parts formed for cooperation with the handle such that the top end of the handle is firmly retained substantially rigid with the cup while the lower end is free to slide within limits relative to the cup so as to allow nesting of the cups when desired or extended into loop form convenient for grasping.

For a more complete understanding of this invention, reference may be had to the accompanying drawing in which—

Figure 1 is a perspective view of a handled cup embodying this invention.

Figure 2 is a view partly in side elevation and partly in section on line 2—2 of Figure 1.

Figure 3 is a section on line 3—3 of Figure 1.

Figure 4 is a plan view of a handle strip before application to the cup.

Figure 5 is a view similar to a portion of Figure 3 but to a larger scale.

Referring to the drawing, at 1 is shown a cup having its side wall formed of a strip of paper having its inner and outer ends 2 and 3, respectively, in overlapping relation and secured together as by a suitable cement. Within the lower portion of the cup is a base member 4 which may be formed as a disk with a downturned margin 5 secured within a marginal portion 6 of the side wall of the cup. Likewise, as shown, the top edge of the side wall is turned outwardly and downwardly to form an external bead 7 which not only stiffens the cup structure but presents a smooth rounded surface to the lips of the user.

As shown best in Figures 2, 3 and 5 the cup side wall is provided with a pair of spaced handle re-

10
 taining strips 10 and 11. These may be formed by cutting pairs of slots 12 and 13 through the outer layer 3 of the cup side wall and these strips 10 and 11 are free from the inner wall end portion 2 so that the end portions of a handle strip 15 may be engaged back of the strips 10 and 11 and between them and the wall end portion 2. The handle strip 15 is formed as a single strip of cardboard, or the like, symmetrical at opposite ends, this strip being of sufficient width to be inserted through the slots 12 and 13 and having widened end portions 16 presenting shoulders 17.

15
 The upper slots 12 are so formed as to leave upwardly extending rounded portions 18 to the strips 10 and 11, these serving as upward extensions behind which the end portions 16 of the handle strip may be readily inserted.

20
 As shown in Figures 1 and 2, the upper end portion of the handle strip is downwardly turned and is inserted through the upper slot 12 back of the strip 10 and is brought down into the slot 13 and the bend 20 is sprung in under the bead 7, thus to prevent undesired lifting of the upper end portion of the handle when it has once been inserted in position. The upper edge of the strip 10, beneath the bend 20 is sufficiently close to prevent any substantial downward motion of the upper end of the handle strip 15. The lower end of the handle strip is also downwardly turned and is inserted through the lower slot 12 behind the cross strip 11. It will be noted that the presence of the handle strip back of the cross strips 10 and 11 serves to deflect the central portions of these cross strips outwardly forming somewhat sharply defined curvatures at 21 adjacent to their ends; there these strip portions turn inwardly toward their junctions with the end portion 3. The shoulders 17 at the upper end of the handle strip 40 tend to remain in lateral alignment with the handle strip adjacent thereto so that these shoulders spring outwardly beneath the portions 21 and prevent ready upward motion of the handle strip which would detach it from behind the cross strip 10. This engagement, as well as the engagement of the bent portion 20 beneath the bead 7, firmly secures the upper end portion of the handle strip without the necessity of any adhesive or mechanical fasteners. The shoulders 17 at the lower end of the handle strip are in position to engage with the curved end portions 21 of the cross strip 11, thus preventing detachment of the strip at its lower end, although permitting it to slide between the operative full line position shown in Figure 2 and the

dotted line position shown wherein the handle strip is collapsed sufficiently closely to the side of the cup so that it may be nested with others in a stack for packing, shipment, or dispensing from a stack in a suitable dispensing device.

The construction of the horizontal retaining strips 10 and 11 as a portion of the outer layer of the lapping ends of the cup side wall is not claimed herein per se, this forming subject matter of my application Serial No. 237,034 filed October 26, 1938.

From the foregoing description of an embodiment of this invention, it should be evident to those skilled in the art that various changes and modifications might be made without departing from the spirit or scope of this invention as defined by the appended claims.

I claim:

1. A paper cup having a wall member provided with an outwardly projecting top marginal bead and provided with a transverse strip element free for a portion of its length from said wall member, and a handle strip having its upper end portion downwardly turned beneath said bead and extending between said free portion and said wall member and having a widened extremity beneath said transverse strip in position to engage thereagainst and prevent detachment of said handle strip, and means for securing the lower end portion of said handle strip to said cup beneath said upper end portion, said handle

strip where said upper end portion is downwardly turned being positioned adjacent to and beneath said bead in position to be held against upward movement by said bead.

5 2. A paper cup having a wall member provided with overlapping ends secured together, the outer of said ends having two pairs of vertically spaced slots therethrough defining upper and lower horizontal strips free from the inner of said ends, and a handle strip of a width to pass through said slots between said strips and said inner end and having widened end portions, each end of said handle strip being extended downwardly and back of one of said horizontal strips.

10 3. A paper cup having a wall member provided with overlapping ends secured together and an outwardly extending bead about its upper end, the outer of said ends having two pairs of vertically spaced slots therethrough defining upper and lower horizontal strips free from the inner of said ends, and a handle strip of a width to pass between the free portions of said strips and the cup wall and having widened end portions, each end of said handle strip being extended downwardly and back of one of said horizontal strips, and the upper end portion of said handle strip lying beneath said bead and being prevented thereby from upward movement relative to the upper of said cup strips.

WILLIAM G. JOPSON.
